(57) **CLAIM**

The ornamental design for a connector assembly, as shown and described.

DESCRIPTION

FIG. 1 is a front and left side perspective view of a connector assembly showing our new design, the front and right side perspective view thereof is a mirror image thereto;

FIG. 2 is a rear and right side perspective view thereof, the rear and left side perspective view is a mirror image thereto;

FIG. 3 is a top plan view thereof;

FIG. 4 is a left side elevation view thereof, the right side elevation is a mirror image thereto;

FIG. 5 is a bottom plan view thereof;

FIG. 6 is a rear elevation view thereof; and,

FIG. 7 is a front elevation view thereof.

The broken line portion of the figure drawings is included for the purpose of illustrating environment and forms no part of the claimed design.
